CLAIMThe ornamental design for an vent breather, as shown and
described.**DESCRIPTION**FIG. 1 is a top, front, left side perspective view of the vent
breather;

FIG. 2 is a bottom, rear, right side perspective view;

FIG. 3 is a front elevation view, the device being rotationally

symmetric, and all elevation views being identical;

FIG. 4 is a top plan view;

FIG. 5 is a bottom plan view; and,

FIG. 6 is a bottom, rear, right side exploded perspective

view.
